UNITED STATES PATENT OFFICE.

WILHELM EBERHARD ERNST, OF BERLIN-SCHOENEBERG, GERMANY.

APPARATUS FOR REGULATING MIXTURE FORMATION IN CARBURETOR SYSTEMS.

Application filed October 6, 1925, Serial No. 60,785, and in Germany July 19, 1924.

The invention relates to carburetor systems for engines whereby one or more chambers are provided between the carburetor and the intake pipe of the cylinder. According to this invention, the inlet cross-sections of the chambers are always greater than the outlet cross-sections, whereby a controlling influence is exerted on the process of mixture formation. It has been shown that the relatively higher pressures attained in this way give better results the closer they approximate to the atmospheric line and variations of pressure are no longer measurable. The tests showed also that the pressure and flow conditions thus realized reacted in an extraordinarily favourable manner on the character of the mixture. It was demonstrated that all measures taken for the further improvement of the mixture in the chambers then gave only a favourable result if the pressure was not thereby lowered. Hence, care must be taken to avoid making the chambers of less cross-sectional area than the throttling cross-sections in such a way that at full load, decrease of pressure takes place. On the contrary, it will be expedient, especially in cases where the intake pipe must be kept as short as possible, to make the chambers greater in cross-section than at the throttling points. It is self-evident that the increased speeds of flow at the throttling points can be used for vaporizing without prejudice to the pressure conditions in these chambers.

The invention is, therefore, designed to further the cooperation of the factors which are of importance in mixture formation, such as:—production of pressure on starting and passage from no-load to the main nozzle and main nozzle system of the carburetor and further the possible addition of supplementary air in accurate proportion to the dynamic pressure.

The invention will now be described with reference to the accompanying drawings which illustrate by way of example several ways of carrying the invention into effect. In said drawings:

Figure 1 is a longitudinal section between two throttling elements, hereinafter referred to as "throttling chambers".

Figure 2 is a longitudinal section through a modified form of throttling chamber,

Figures 3 and 4 are longitudinal sections through similar throttling chambers, according to other modified forms,

Figure 5 is a longitudinal section through a further special form of the throttling chamber,

Figure 6 is a longitudinal section through such a throttling chamber, showing a special valve gear for both the throttling elements,

Figure 7 is a view of a form of the parts of the valve gear for one of the two throttle valves, according to Figures 1, 3, 5 and 6,

Figure 8 is a longitudinal section through such a throttling chamber with several throttling elements,

Figure 9 is a longitudinal section through a throttling chamber for a vertical carburetor, in a special form of execution.

Two throttle organs or valves 2 and 3 are fitted, rotatively, in a casing 1 and they are arranged in such a way that the throttle valve 3, on load being applied to the motor, always shows a larger aperture than the throttle valve 2. In the space defined by the two throttle valves, described in the text following as throttle chambers, a reduction of the vacuum depression, that is to say, an approach to atmospheric pressure, takes place and thereby the fuel nozzles are made substantially dependent upon the dynamic depression, as such is determined by the number of revolutions and the load of the motor. In the form of execution delineated, apertures 4 are provided, which are controlled by an annular slide valve 5. This is in the event of an addition of supplementary air being desired. The valve 5 is mounted on a frusto conical valve seat 6, in order to ensure the requisite tightness. By the arrangement of the openings for the supplementary air in the space between the two throttle organs or valves, in which a practically constant pressure obtains, the supply of supplementary air is caused to depend perfectly upon the load of the motor and the number of its revolutions. In this manner, the admission of too much supplementary air is positively prevented. With a heavier load and a reduced speed, and therefore, for example, on a sudden opening

of the throttle organs or valves with a slow drive, a relatively small quantity of supplementary air, with an unchanged section for the supplementary air, is fed to the motor, so that a sufficient abundance of mixture, with its corresponding effect on the motor, is assured. This is due to the fact that there is no high static depression present which

would produce an excessive aspiration of air. A no-load passage 7 is fitted in the usual way to the first throttle valve 3 in the direction of flow. (Arrow 8.)

As regards Figure 2, the side walls 10 and 11 of a rotary valve are used in a casing 9 as throttle organs. The position of this valve is shown in full lines with a comparatively small opening, whereas the dot and dash lines 10^a and 11^a show the position at full opening. It will be seen from the drawing that when the rotary slide valve is fully open, by narrowing the cross-section of the passages, both on entering and also on leaving the rotary slide valve, the throttling effects can be maintained. The supplementary air is here admitted, by way of example, through an opening 12 made in the cover plate of the slide valve. This opening is controlled by an opening 13 in a cooperating plate 14 of any desired design. The full lines show exactly how the orifice 12 is opened and a quantity of extra air is admitted. The dot and dash opening 13^a shows how, on full opening of the throttle organs 10 and 11, the full opening of the orifice 12 is already exceeded, whilst only a small quantity of extra air is admitted. This arrangement is designed to work with medium throttle openings and with a specially economical mixture, under the heaviest load of the motor, and to give a high efficiency result. With this object the plate 14 is placed between the slide valve and the cover of the casing and held in position by the pressure of a spring. The stop of the plate is conveniently placed in the casing cover and can, with advantage, be made adjustable or regulated from the operator's seat. This arrangement permits adaptation of the added supplementary air for various kinds of fuel and heat conditions of the motor.

The dot and dash lines 15 and 16 show how the space between the throttle organs may be enlarged to bring the pressure in the throttle chamber into closer relationship with the atmospheric pressure. One or more passages 15^a or 15^b may, by way of example, be provided in the wall 10 for the draining of the mixture from the throttle chamber into the no-load section.

In the form of execution, according to Figure 3, the inlet of the supplementary air into the space between two throttle valves 17 and 18 or any other desired throttle organs is controlled by a slide valve 19. The working of the slide valve is effected by any desired means as, for instance, an eccentric 20, which works on a flange 21 on the slide valve, whereby a spring 22 keeps this slide valve always against the eccentric. In place of the eccentric, of course, any other similarly acting device may be used, such as curved discs and the like.

With a special form of execution a wedge-shaped ring 23 is provided which acts on the shaft 24 of the eccentric and can move this shaft in an upward direction. The object of this arrangement is, for example, when working with a cold motor to admit less supplementary air than when working with a warm motor, thereby retaining, in both cases, the due degree of opening of the slide valve produced by the eccentric or the curved disc.

In the example, according to Figure 4, a conical throttle organ 26 and a similarly designed throttle organ 27, following the stream line, are provided in a conical casing 25, the whole constituting a throttle chamber 28. The inclination of the casing walls 29 in the length of stroke of the throttle organ 26 is, in this case, different from the inclination of the casing walls 30 in the length of stroke of the throttle organ 27. The effect of this is that the opening of the throttle organ 26 is always greater than the opening of the throttle organ 27.

The fuel for the operation without load is admitted, in the usual way, through an opening 31. The throttle bodies may, of course, be constructed in a stream line shape.

In the example, according to Figure 5, a boring out, or the like 34 in a housing 32 in the course of the inner walls 33 of this housing was effected, whereby a sharp reduction 35 resulted. At a distance from the same there are openings 36 made for the supplementary air, which are controlled in any desired way, as, for example, by a slide valve 37. Throttle valves 38 and 39 are provided, as in Figure 1. By this arrangement the introduction of the supplementary air into the throttle chamber is made dependent in greater measure upon the number of revolutions of the motor, because, in this case, a particularly pronounced injector action of the mixture flowing through the housing takes place. By this special construction, an extension of cross-section is simultaneously produced in the throttle chamber itself, which, in many instances, has a favourable effect.

In the forms of execution described in the foregoing, it is understood that, in the case of the two throttle organs in the stream line of the mixture, the throttle organ lying first in the direction of flow always exercises a lesser throttling effect than the following throttle organ in the direction of flow.

In Figure 6 a form of execution is shown which is particularly useful for the control of the no-load and of the passage from the no-load to the main nozzle or the main nozzle system of the carburetor. Here are placed two throttle valves 40 and 41 in a similar way to those in the example, according to Figure 1. The throttle valve 40 is firmly fixed on a shaft 42, which is controlled by

a lever 43. The throttle valve 41, on the contrary, has a shaft 44 which can rotate opposite to another constructional part 45, also of desired design, which part is controlled by a lever 46 and a guide 47 in dependence upon the lever 43 of the other throttle valve. An arm 48 is fixed to the valve 41, which arm, under the action of a spring 49, impinges on a stop 50 and keeps the throttle valve 41 slightly open, if the other throttle valve 40 is closed or is in the no-load position. On the part 45 a further arm 51 is fixed, having a stop 52. The latter can be so adjusted that, on the oscillation of the two levers 43 and 46, the throttle valve 41 only sets up a corresponding oscillation when the throttle valve 40 shows a larger opening than the throttle valve 41, as may be seen by the dot and dash line in 40^a.

The effect of this arrangement is that when the throttle valve 40 is in the no-load position the throttle valve 41 is always open, so that there is always a sufficient depression at a no-load nozzle 53 which ensures the passage of the fuel through the no-load nozzle.

Another effect of this arrangement, simultaneously realized, is that the passage from the no-load nozzle to the main nozzle is extremely uniform and gentle, inasmuch as, by approximation of the depression in the throttle chamber to the atmospheric pressure, the delivery from the no-load nozzle is completed at the right time if the main nozzle has taken up the correct supply of fuel for the composition of the mixture.

A similar result is achieved with the rotary slide valve, as may be seen in Figure 2, through the passages 15^a and 15^b.

In the form of execution, according to Figure 7, a throttle valve 55 and a lever body with three lever arms 56, 57 and 58 are rigidly fixed to the shaft 54. The lever 56 is intended to impinge against a set screw 59 in the wall of the carburetor or of a stud attached thereto, thus giving the minimum opening to this valve, such opening being necessary for the attainment of the requisite depression in the throttle chamber. On the shaft 54 of the throttle valve 55 an accelerator lever 60, loosely rotatable, is fitted, which is served, in the usual manner, by a tension member 61 and is held by a spring 62 or other means as against the action of the tension member. A head piece 63 is fitted to the accelerator lever, which lies within the range of a set screw 64 or 65 in the lever arms 56 and 57. The last named arm is connected to the head 63 by a spring 66.

By this arrangement, the throttle valve 55 is kept in the minimum opening position by the pull of the accelerator spring 62 and the stop of the arm 56 against the set screw 59,

counterbalancing the action of the spring device 66.

The operation of the accelerator tension member 61 oscillates the accelerator lever 60 in certain measure and it is only after impinging against the set screw 65 that the throttle valve 55 is brought to a further opening.

The shaft 54 of the throttle valve is connected with the shaft of the other throttle valve by levers and a connecting rod, similar to the way indicated in Fig. 6, so that the other throttle valve begins its movement at the commencement of the pull in the accelerator tension member; the throttle valve 55, on the contrary, only begins the opening movement and then further participates when the head-piece 63 impinges against the set screw 65.

Instead of only two throttle organs several mutually controlling throttle organs may, of course, be used in the same circumstances. The throttle organ may either form a part of the carburetor or serve as an adjunct to same.

Figure 8, by way of example, shows such an arrangement wherein three throttle organs or valves, 67, 68, and 69, are provided. These three throttle organs or valves are positively connected one with the other and controlled so that each succeeding throttle organ or valve, proceeding from the carburetor point 70, provides a smaller opening than the preceding throttle organ or valve. Such a carburetor is fitted in the usual manner to the motor block 71.

Figure 9 illustrates another arrangement wherein a suction conduit 74 is provided between the mixture forming place 72 and the openings 73 leading into the cylinder chambers of the motor. Between mixture forming place 72 and openings 73 are arranged throttle organs or valves 75 and 76, so connected with each other that a larger opening is provided by the valve 75 than by the valves 76. If desired, another throttle organ or valve 77 may be provided, as indicated in dot and dash lines in Figure 9. In this case, also, the plurality of throttling organs or valves 75, 77, and 76, respectively provide successive smaller openings for the flow of the fuel mixture from the main mixture forming place 72 to the openings 73 leading into the cylinder chambers of the motor.

Even in the case of over pressure of the mixture compressor motor a better regulation of the formation of the mixture is achieved by the arrangement, according to the invention.

In order to adapt the arrangement to the different conditions of pressure (for instance, suction pressures) the throttle organs set behind each other may be placed opposite each other in such a way that the

two throttle organs, from the commencement of the load on, are not opened to the same extent, for instance, at the same throttle valve angle, but that the throttle 5 organ coming first in the direction of flow of the mixture, outpaces the other throttle valve. Thereby the measure and the extent of the advance (an increasing and, in a given case, a decreasing advance) is suitably 10 adapted to the existing conditions in the machine, in the sense that the nearest possible approximation to the atmospheric pressure is attained in all phases of working.

What I claim and desire to secure by Letters Patent of the United States is:—

1. In combination with the intake conduit of an internal combustion engine, a pair of throttle valves in said conduit spaced from each other to define a mixing space, and unyielding connecting means between said valves holding them at a fixed angular relation to each other so that a change in the degree of opening of one causes a corresponding change in the degree of opening 25 of the other, the valve positioned nearer the motor being at all times inclined to the axis of said conduit to a greater extent than is the other valve.

2. In combination with the intake conduit 30 of an internal combustion engine, a pair of throttle valves in said conduit spaced from each other to define a mixing space, unyielding connecting means between said valves holding them at a fixed angular relation to each other so that a change in the degree of opening of one causes a corresponding change in the degree of opening 35 of the other, each of said valves being adapted when in closed position to substantially 40 close the conduit, the valve positioned near the motor being at all times inclined to the axis of said conduit to a greater extent than is the other valve, and means limiting the angular movement of said valves.

45 3. In combination with the intake conduit of an internal combustion engine, a pair of throttle valves in said conduit spaced from each other to define a mixing space, unyield-

ing connecting means between said valves holding them at a fixed angular relation to each other so that a change in the angular position of one causes a corresponding change in the angular position of the other, a conduit for supplemental air opening into said mixing space, and means controlled by 55 the movements of said valves for opening and closing said last mentioned conduit.

4. In combination with the intake conduit of an internal combustion engine, a pair of throttle valves in said conduit spaced from 60 each other to define a mixing space, unyielding connecting means between said valves holding them at a fixed angular relation to each other so that a change in the angular position of one causes a corresponding 65 change in the angular position of the other, the valve nearer the motor being at all times inclined to the axis of said conduit to a greater extent than to the other, the wall of said conduit being provided with a port 70 for admitting supplemental air to said mixing space, and means controlled by the movements of said valves for opening and closing said port.

5. In combination with the intake conduit 75 of an internal combustion engine, a pair of throttle valves in said conduit, each valve being adapted to substantially close the conduit to control the flow of fuel mixture through said conduit, said valves being 80 spaced from each other to define a mixing space, unyielding connecting means between said valves holding them at a fixed angular relation to each other so that a change in the angular position of one causes a corresponding 85 change in the angular position of the other, the valve nearer the motor being at all times inclined to the axis of said conduit to a greater extent than the other, the wall of said conduit being provided with a 90 port for admitting supplemental air to said mixing space, means controlled by the movements of said valves for opening and closing said port, and a no-load air passage leading to said mixing space.

WILHELM EBERHARD ERNST.
